Inventor:

Charles B. Royal,
By Dyerforth, Lee, Critten, & Miles,
Att. G. S.

UNITED STATES PATENT OFFICE

CHARLES B. ROYAL, OF CHICAGO, ILLINOIS

LUBRICATOR FOR RAILWAY JOURNAL BOXES

Application filed March 30, 1928. Serial No. 265,828.

This invention relates to lubricators for railway journal boxes and the like and is fully described in the following specification and shown in the accompanying drawings, 5 in which:

Figure 1 is a longitudinal vertical section on the line 1 of Fig. 2;

Fig. 2 is a transverse section on the line 2 of Fig. 1;

10 Fig. 3 is a perspective view of the lubricator removed from the journal box; and

Fig. 4 is a view similar to Fig. 2 but showing a journal box with the lubricator cast integral therewith.

15 The embodiment shown in Figs. 1 to 3 comprise a journal box 10 of a well known type adapted to receive the usual brass bearing 11 which rests upon the top of the journal 12.

It has heretofore been customary to fill the 20 bottom of the journal box 10 with waste and grease, the waste extending up into contact with the bottom and sides of the journal 12 so that a film of lubricant is continuously supplied to the journal 12 as it rotates. The 25 present invention aims to supply this lubrication with a much more uniform coat of lubricant and to do so more thoroughly and efficiently.

To do this I have provided a separate lubricant receptacle 13 which is preferably made 30 of sheet metal and which in cross-section is of a generally V-shape. The upper ends of the sides 14 and 15 extend somewhat away from the journal 12 as shown in Fig. 1 and

35 provide spaces 16 and 17 which are wider at the top than at the bottom and which are still more narrowed at the bottom by means of inwardly extending portions 18 and 19 which provide constricted sections 20 and 21.

40 Waste or the like placed between the journal 12 and the side 14 will have a slight tendency to move down toward the restricted portion 20 as the journal 12 is rotated in a counter-clockwise direction. Likewise waste lying

45 beneath the journal 12 will have a tendency to be carried up by this same counterclockwise direction and be wedged against the journal by the constriction 21. A movement of the journal 12 in a clockwise direction will 50 also have the tendency to move the waste in

the space 17 downwardly and to wedge it against the journal in the constriction 21. A pin 22 is carried by the bottom of the journal box, engages a recess 23 in the bottom of the lubricant receptacle and prevents movement 55 of the receptacle.

Thus it will be seen that a very simple and convenient lubricator is provided for railway journal boxes of this type and one which provides a receptacle 13 beneath the bearing for 60 oil so that dirt and moisture in the bottom of the journal box will be largely excluded from the oil in the receptacle. The receptacle may be introduced into the journal box through the journal box cover 24 which is removable in a well known manner about the hinge pin 25.

The lubricator shown in Figs. 1 to 3 is 65 that which is designed for use with railway journals now in service. In manufacturing 70 new journal boxes however it may be desirable to make this an integral part of the box and this is accomplished by casting the oil receptacle 26 and the sides 27 and 28 integral 75 as shown in Fig. 4. The box is then filled with waste and the like and a suitable lubricant, preferably oil, is poured over this waste and runs down into the receptacle 26 where it passes by capillary attraction to all parts 80 of the waste above it. Of course, a spring supported felt pad, or the like, such as is commonly used in journal boxes, may be employed instead of the waste or in addition thereto.

It will be observed that the sides 27 and 28 85 not only serve as retaining members for supporting the lubricant containing material, but also serve as bracing members which directly buttress the bottom of the journal box. Thus, independent of the lubricating means disclosed, the side walls 27 and 28 serve to 90 protect or reinforce the bottom or floor of the journal box, when pressure is exerted thereon. This advantage is particularly useful when the journal box is lifted or raised for the purpose of removing or inserting bearings within the box. It is a well known practice when removing or inserting bearings in this manner to place a jack or lifting member 95 directly below the floor of the journal 100

box, thus exerting great pressure upon the floor or bottom of the journal box. Members 27 and 28, as more clearly shown in Fig. 4, serve to protect and reinforce the floor of the box during this operation.

6 The vibration of the axle and journal box causes the waste or packing to settle gradually into the lower portions of the spaces 16 and 17 thereby causing it to hug the journal more tightly.

10 The end walls of the receptacle lie just beneath the journal so that the oil level can be kept quite close to the bottom of the journal. Thus oil has to be lifted but a short distance to the point where it is applied to the journal.

15 While I have shown and described but a single embodiment of this invention, it is to be understood that it is capable of many modifications. Changes therefore in the construction and arrangement may be made which do not depart from the spirit and scope of the invention as disclosed in the appended claims.

I claim:

20 1. In a device of the character set forth, a railway journal box, provided with bottom and side walls, interior inclined walls connecting the bottom wall and side walls of said journal box, and end wall members connecting the lower portion of said interior walls so as to form therewith a lubricant compartment below the journal.

25 2. In a device of the character set forth, a railway journal box, a removable lubricant receptacle adapted to confine therein a body of oil and adapted to be placed within said box, said receptacle being provided with walls approaching said journal and being provided with end walls adapted to stand below said journal, and means for securing said receptacle in position below said journal.

30 In testimony whereof I have hereunto set my hand this 20th day of March, 1928.

CHARLES B. ROYAL.
